O. W. VALLIER

WATER MIXING VALVE

Filed April 6, 1925

By Harry De Wallace
Attorney

UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

WATER-MIXING VALVE.

Application filed April 6, 1925. Serial No. 21,066.

To all whom it may concern:

Be it known that I, ORVIS W. VALLIER, a citizen of the United States, residing at Watertown, in the county of Jefferson and State of New York, have invented certain new and useful Improvements in Water-Mixing Valves, of which the following is a specification.

This invention relates to improvements in mixing-valves designed for supplying water to tub and shower baths, lavatories, sinks, and the like, by means of which cold and hot water may be dispensed by a single valve and a single control.

The object of the invention is to provide a casing whose interior is formed with a valve-chamber, in which is rotatably disposed a valve, the said valve being formed with a concentric mixing-chamber which communicates with the valve-chamber, by means of radial ports; the said casing being formed at opposite sides with hollow arms that respectively supply cold and hot water; the ports of the valve being disposed in the same plane as the axis of said arms, and adapted when the valve is rotated, to conduct the water into the mixing-chamber. A further object is to provide a stem which is fitted with a handle for operating the valve.

A further object is to provide means for reciprocating the stem axially relatively to said chambers for dispensing the cold and hot water. A further object is to provide an adjusting member that is arranged concentric to the stem and cooperates with said reciprocating means for holding the valve in its seat. A further object is to provide means for stopping the rotary movements of the stem and valve immediately the valve is closed. A particular object of the present invention is to provide novel and simple means for preventing leakage of water through the top of the valve casing, comprising a non-rotatable washer-like part,

which is mounted upon the adjusting member concentric to said member and said stem, a relatively thick circular packing member which overlies said washer, and is held in place by a cap, which closes the top of the casing and compresses the packing in a manner to prevent leakage around the adjusting member and stem.

This invention relates particularly to improvements in the mixing valves shown and described in my pending applications Serial

Nos. 2,346 and 15,955, filed respectively January 14, 1925, and March 16, 1925.

I attain these objects by the means set forth in the detailed description which follows, and as illustrated by the accompanying drawings, in which—

Figure 1 is a central vertical section, taken on line 1—1 of Fig. 2. Fig. 2 is a horizontal section taken on line 2—2 of Fig. 1, showing the valve positioned for dispensing cold water. Fig. 3 is a horizontal section taken on line 3—3 of Fig. 1. Fig. 4 is a similar section, taken on line 4—4 of Fig. 1. Fig. 5 is a similar section, taken on line 5—5 of Fig. 1. Fig. 6 is a broken horizontal section taken on line 2—2 of Fig. 1, showing the valve set for mixing cold and hot water. Fig. 7 is a similar view, showing by full lines, the valve positioned for drawing only hot water; the dotted lines of this view showing the valve closed. Fig. 8 is a horizontal section taken on line 8—8 of Fig. 9, showing a four-way valve, the valve being positioned, as in Fig. 7, for dispensing warm water. And Fig. 9 is a central vertical section taken on line 9—9 of Fig. 8.

In the drawing, the mixing valve comprises a casing or body 2, which is formed with a hollow cylindrical portion 2', a hollow neck 2^a that aligns axially with said portion 2', and with a tapered valve seat 2^b, between said portions. At opposite sides of the casing are disposed arms 3 and 4, which are arranged at right angles to the axis of the valve chamber and respectively conduct cold and hot water to the chamber 2^b, by means of aligning ducts 3'—4'. The arms 3 and 4 are shown threaded into the casing, but these parts may be integral with the casing.

The dispensing of cold and hot water independently, as well as the mixing of said water, is effected by means of a valve 6, which is formed with a cylindrical portion 6' that conforms substantially to the bore of the body portion 2', while its opposite end is tapered, as at 6^a, to conform to the seat 2^b. The valve is normally hollow throughout, and its tapered portion is preferably formed with a mixing chamber 6^b, which is adapted to communicate with the ducts 3'—4', by means of radial ports 6^c—6^d, when the valve is rotated, as best seen in Figs. 1, 2, 6, 7, 8 and 9. Above the mixing chamber the bore of the valve 6 is reduced,

and above said portion the body is formed with an enlarged socket or cavity 6^e. The top end of the valve body is formed with diametric slots 6^f. The valve 6 is preferably nonmetallic for reducing friction and wearing of the parts. The valve is rotatable by means of a stem 7, which is loosely disposed in the axial bore of the valve body, and has a reduced lower end portion 7' that extends into the chamber 6^b. This end of the stem is formed with a threaded hole to receive a screw 8, which supports a disc 8', the said disc being larger in diameter than the stem and preventing the stem from being accidentally withdrawn from the body. The reduced portion 7' of the stem is longer than the adjacent contracted bore of the valve body and allows the stem a slight movement axially relatively to the body, as may be understood by comparing Figs. 1 and 9. The medial portion of the stem is enlarged, as at 7^a, and this portion is normally disposed in the cavity 6^e, the said portion being perforated diametrically to receive a pin 9, which is loosely positioned in the slots 6^f, and is employed for driving the valve, as well as for preventing rotation of the stem in the valve. Above the socket 6^e the stem is formed with coarse box-threads 7^b, and above the said threads the stem is reduced again, as at 7^c, and its top end is fitted with a handle 10, by which the stem and valve may be rotated as one part. The threaded portion 7^b of the stem is engaged by a cylindrical nut 12, the latter having a flange 12', and said flange being formed with oppositely facing peripheral lugs or ears 12^a, which are disposed in similar longitudinal guide-ways or grooves 2^x of the casing, for rendering the nut non-rotatable. The valve 6 is held operatively in its seat by the nut 12, an adjusting member 13, which is threaded into the top end of the casing 2', and a sleeve 14 which is disposed between the nut and the body of the valve (see Fig. 1). By the foregoing construction and arrangement of the parts, the stem when rotated by the handle is reciprocated by means of its threads engaging the nut 12, to the extent allowed by the vertical play of the pin 9 in the groove 6^f. For example, when the handle 10 is swung in one direction, the stem is carried upwardly by the nut 12, and the pin 10 engages the bottom end of the sleeve 14. This stops the further rotation of the stem. When the handle is swung in the opposite direction, the enlargement 7^a bottoms in the cavity 6^e, which again stops the rotary movement of the valve and stem. The spacing of the disc 8' and the said enlargement determines the greatest distance the stem may be moved axially. The member 13 is provided with sockets 13', for the use of a spanner wrench, by which its adjustments may be effected. When the mixing valve is assembled, the member 13 is screwed downwardly until it bears against and forces the nut 12 and the sleeve 14 in the direction for operatively seating the valve 6. The member 13 is then left in that position until the valve or its seat becomes worn to an extent that requires readjustment. Upon the top face of the member 13 is disposed a washer-like guard 15, whose normal diameter corresponds to that of said member. The washer 15 is provided with similar peripheral ears 15' that engage the grooves 2^x of the casing, like the flange of the nut, for preventing rotation of the washer. Upon the washer 15 is then disposed a relatively thick layer or sheet of packing, as 16, the said packing preferably being large enough in diameter to overlap the top-end of the casing 2', as shown in Fig. 1, thereby tending to prevent water, that might well-up in the casing, from leaking through the threaded joint of the parts 2' and 13. The packing 16 is compressed against the washer and the casing, by means of a screw-cap 17, which engages external threads of the casing. For this purpose, the inner face of the cap is arched, as at 17', and when the cap is screwed down tightly upon the packing, the latter becomes compressed downwardly as well as radially against the stem and the casing for preventing leakage, between or around the said parts. The particular use of the guard 15 is to prevent the packing, which is more or less adhesive, from accidentally disturbing the adjustment of the member 13, in case the packing tends to rotate with the cap 16, when the latter is screwed in either direction. This is an important feature of the invention since it effectually obviates all danger of the valve being loosened relatively to its seat and causing leakage, when the valve, while idle, is subjected to the usual service pressure, which ordinarily ranges from sixty to eighty pounds.

According to the showing in Figs. 1 and 2, when the handle 10 is in the full line position (which corresponds to the full line radial arrow in Fig. 2), the port 6^e of the valve is positioned to draw cold water from the arm 3 into the chamber 6^b, from which the water may gravitate towards the neck 2^a, and thence through a discharge member 18. When the handle is swung to the central dotted position (see Fig. 1, and the radial arrow in Fig. 6), the ports 6^e and 6^d are in communication respectively with the cold and hot water ducts 3'-4', which effects the dispensing of warm water. And when the handle 10 is swung to the right dotted position of Fig. 1 (see also full line radial arrow in Fig. 7), the valve is positioned for drawing only hot water from the arm 4. The reversing of the handle 10, likewise reverses the order of the dispensing of the cold and

hot water. The closing of the valve 6 is effected by swinging the handle 10 to correspond to either of the positions shown by the dotted arrows in Figs. 2 and 7.

5 In Figs. 8 and 9 is shown a four-way mixing valve, whose casing 2^e is formed with a cold water receiving arm 3^a, which connects with the valve chamber 2^b by a passage 3^b, and a hot water arm 4^a that connects with 10 the chamber 2^b by a similar passage 4^b. In this modified casing, the valve 6 and related and controlling parts are intended to be the same in all respects, as shown in Figs. 1 and 2, and said valve is shown in a position corresponding to the showing in Fig. 6, for dispensing warm water. In Figs. 8 and 9 the water gravitates from the mixing chamber 6^b into a relatively large compartment 2^a, which is in normal unrestricted communication 15 with similar diametrically arranged discharged openings 2^e—2^f, that are adapted to carry the water dispensed by the valve, as for example, to a bath tub, as well as to a shower head (not shown), as shown by the 20 drawings of my pending applications.

My improved mixing valve is extremely simple, and affords novel, convenient and effective means for controlling the supply of water at different temperatures, by means of 30 a single control. The means for preventing accidental disturbance of the valve after it has been properly adjusted relatively to its seat, as by the rotation of the screw-cap 17, and the disposition and arrangement of the 35 washer 15 which prevents ready access to, or tampering with the adjusting member 13, enables me to produce a fluid dispensing valve with fewer parts, which is more compact and durable, and is less liable to leak or otherwise become disordered, than any of 40 the older fittings of the class, known to me. The packing 16 is the only means required for preventing leakage of the mixing valve, and when said packing is applied, as herein shown and described, and the cap 17 and other related parts are properly adjusted, the valve will withstand constant use for 45 long periods of time, without attention or care of any kind.

50 Having thus described my invention what I claim is—

1. In a mixing valve the combination with a hollow body formed with a valve chamber and a threaded barrel, a valve rotatable in 55 said body, a stem connected to said valve, said stem being partially threaded, of a threaded adjusting member adapted to be screwed into the barrel of the body for normally holding the valve operatively seated, a non-rotatable nut engaging the threads of 60 the stem and controlling the rotary movements of the valve, said nut cooperating with said adjusting member for controlling the seating of the valve, a disc overlying said 65 adjusting member and being interlocked

with said barrel for preventing rotation of the disc, a packing for sealing the threaded joint between said adjusting member and said barrel and surrounding the stem beyond the disc, and a screw-cap for closing the end 70 of the barrel, adapted for compressing the packing tightly against the stem.

2. In a mixing valve the combination with a hollow body formed with a valve chamber and a threaded barrel, a valve rotatable in 75 said body, and a stem loosely connected to said valve, said stem being partially threaded, of a threaded adjusting member adapted to be screwed into the barrel of the body for normally holding the valve operatively seated, a stationary nut engaging the threads of the stem and controlling the rotary movements of the valve, said nut co-operating with said adjusting member for controlling the seating of the valve, a disc 80 overlying said adjusting member and being interlocked with said barrel for preventing rotation of the disc, a packing for sealing the threaded joint between said adjusting member and said barrel, said packing being 85 supported by said disc and surrounding the stem beyond the disc, and a screw-cap for closing the end of the barrel, the inner side of said cap being arched and adapted for compressing the packing tightly against the 90 stem.

3. A mixing valve including a body formed with a valve chamber and a hollow threaded portion, a valve rotatable in said chamber, a stem for operating the valve, said stem protruding through the hollow portion and being threaded beyond the valve, a member engaging the threads of the stem and controlling the rotary movements thereof, a threaded disc beyond said 100 member adapted to cooperate with said member for adjusting and holding the valve in its seat, a packing for preventing leakage of water beyond said member, means interposed between the packing and said disc for preventing accidental rotation of the disc and disturbing the adjustment of the valve, and a screw-cap closing the end of the threaded portion and being formed internally for compressing the packing 105 downwardly and radially.

4. In a mixing valve the combination with a hollow body formed with a valve chamber and a threaded barrel, and a valve 110 rotatable in said body, of a spanner adjusting nut adapted to be screwed in to the barrel for normally holding the valve operatively seated, a stem loosely connected to the valve and passing axially through said nut, said stem being partially threaded, a member engaging the threads of said stem below said nut adapted to reciprocate said stem during the rotation of the valve, a packing for sealing the open end of said 115 barrel beyond said nut, a washer interposed 120

between said packing and said nut, means for preventing rotation of said washer, and means for compressing the packing for sealing the joints between said member and said barrel as well as between the stem and said washer.

5. In a mixing valve, the combination with a hollow body having a valve chamber therein and having a threaded barrel extending beyond said chamber, and a valve rotatable in said chamber, of a stem for operating said valve, said stem being disposed axially in said barrel and having a threaded portion above the valve, an adjusting nut adapted to be screwed into the barrel concentric to the stem, a non-rotatable member engaging the threads of the stem for reciprocating the stem, said member being interposed between said nut and said valve, a packing for sealing the end of the barrel, a cap for closing the said end and for compressing the packing, and a non-rotatable disc interposed between the packing and the adjusting nut, and preventing the rotation of the packing from disturbing the adjustment of said nut.

6. In a fluid mixing device, a body formed with a valve chamber and with a threaded cylindrical portion extending axially away from said chamber, a valve in said chamber, a stem for rotating said valve, means for effecting the reciprocation of said stem during the rotation of the valve and for stopping the rotary movements of the stem and valve at the end of each dispensing operation, an adjusting member threaded into said cylindrical portion adapted to adjust and hold the valve relatively to its seat, a guard for protecting said adjusting member said guard being mounted upon said member and having peripheral lugs that engage said cylindrical portion for prevent-

ing rotation of said guard, a disc-shaped compressible packing mounted upon said guard and overlying the open end of the cylindrical portion, said packing having an opening to receive the stem, and means for compressing the packing and for forcing it tightly against the stem and said guard.

7. In a mixing valve for dispensing water at different temperatures, the combination with a hollow body formed with a valve chamber and with a threaded portion beyond said chamber and having cold and hot water inlet ducts communicating with said chamber, of a valve rotatable in said chamber and having radial ports adapted to respectively control the flow of the cold and hot water into said chamber, a stem for rotating said valve said stem passing axially through said threaded portion, means for reciprocating said stem when the latter is rotating the valve and for stopping the rotary movements of the stem immediately the valve is closed, a disc adjustably supported in said threaded portion adapted to control the operative seating of the valve, a cap for closing the open end of said threaded portion, a packing member partially filling the hollow side of said cap concentric to and in contact with the stem and also overlying the open end of said threaded portion, said packing adapted to be compressed by said cap against said stem and also against said threaded portion for preventing leakage in case the water wells upwardly in said portion, and means interposed between said disc and said packing for preventing the packing from disturbing the adjustment of the valve in case the packing rotates with the cap.

In testimony whereof I affix my signature.

ORVIS W. VALLIER.
